UNITED STATES PATENT OFFICE.

CHARLES J. BRUNSELL AND JOHN JOHNSON, OF MINNEAPOLIS, MINNESOTA.

SCRAPER-SHARPENER.

1,190,718.

Specification of Letters Patent.

Patented July 11, 1916.

Application filed August 9, 1915. Serial No. 44,432.

To all whom it may concern:

Be it known that we, CHARLES J. BRUNSELL and JOHN JOHNSON, citizens of the United States, residing at Minneapolis, in the 5 county of Hennepin and State of Minnesota, have invented certain new and useful Improvements in Scraper-Sharpener; and we do hereby declare the following to be a full, 10 clear, and exact description of the invention, such as will enable others skilled in the art to which it appertains to make and use the same.

Our invention has for its object to provide an extremely simple and highly efficient tool 15 or device for sharpening scrapers of the steel scraper blade type, such as used in scraping wood surfaces by hand, or for that matter, for the use of machines such as employed in scraping floors.

Generally stated, the invention consists of 20 the novel construction and combination of parts hereinafter described and defined in the claims.

The improved scraper sharpening device 25 is illustrated in the accompanying drawings wherein like characters indicate like parts throughout the several views.

Referring to the drawings: Figure 1 is a 30 perspective view of the improved device; Fig. 2 is a plan view thereof; Fig. 3 is an end elevation of the device showing the front end thereof, to-wit, that end which is in the vicinity of the line marked $x^3 x^3$ of Fig. 2; Fig. 4 is a section taken on the line 35 $x^4 x^4$ of Fig. 2; Fig. 5 is a plan view of the device; Fig. 6 is an elevation looking at the front end thereof, to-wit, that end which is in the vicinity of the line $x^6 x^6$ of Fig. 5; and Fig. 7 is an end elevation showing a 40 flat file held by the device for use in sharpening the scraper blade.

The body 1 of the device is preferably 45 made of wood and is of an elongated rectangular general form. On its upper face, it is formed with a raised portion 2 that is rectangular in cross section, and at the sides of which are grooves 3. Outward of the said grooves are guide surfaces 4 that incline slightly outward, being at a right angle to a horizontal or to the upper face of the rectangular central portion 2. In the sides of the body 1 are grooves 5 that are adapted to receive a portion of a flat file y .

The numeral 6 indicates a rectangular

steel blade tempered very hard. The edges 55 of this blade 6 are at a right angle to the faces thereof, and the said blade is tightly set into a groove cut in the raised portion 2, both transversely, and vertically oblique to the faces and sides of the raised portion 2. This 60 doubly oblique arrangement of the said blade in the raised portion 2 is highly important because it presents the upper and end edges of the said blade at the proper angle for action on the steel scraper blade y^1 , 65 which is to be sharpened. Also it is highly important that the upper and end edges of the said sharpening blade 6 project but slightly beyond the upper and side edges of the said raised portion 2, substantially as 70 illustrated in the drawings.

The use of the device for sharpening the scraper blade y is substantially as follows: First the scraper blade, held as shown in Fig. 2, is drawn toward the operator with 75 its flat undersurface held against the upper edge of the sharpening blade 6 (see Figs. 2 and 3). By repeating this drawing action on all four of the edge side faces of the scraper blade y , the fins on the four edges of 80 the said scraper blade will be turned outward into the plane of the faces of the scraper blade. Then by placing the scraper blade (as shown by dotted lines in Figs. 5 and 6) on one of the slightly inclined guide 85 surfaces 4, and drawing the same rearward with the edge of the scraper blade against the ends of the sharpening blade, the fins on the edges of the scraper blade will be turned outward and the scraper blade will be put 90 in the best possible condition for scraping. In practice we have found that by the use of this sharpening tool, scraper blades may be very quickly and efficiently sharpened, and that this may be accomplished by any 95 person with a very little practice, whereas, very considerable skill and considerable more time is required to sharpen a scraper blade by the old or ordinary operation, wherein a steel bar is drawn over the edges 100 of the scraper blade. Obviously, the various guide surfaces on the body member 1 make it an easy matter to properly direct the edges of the scraper blade against the edges of the sharpened tool. When the edges of the 105 scraper blade, from repeated sharpening, become rounded, they may be resharpened by inserting the file y into one of the grooves 5

and then drawing the scraper blade over the same, as shown in Fig. 7, using one edge of the body 1 as a guide for the scraper blade.

What we claim is:

- 5 1. A scraper sharpener device, comprising a body having a raised elongated portion and a guide surface at one side below the upper surface thereof, and a hard sharpening blade set into the raised portion of said 10 blade having oblique end and edge portions projecting respectively beyond the side and top surfaces of said raised portions.
- 15 2. A scraper blade sharpening tool comprising a body having a raised rectangular portion and guide surface outward of the side edges and below the top surface of said raised portion, and a hard sharpening blade set into said raised portion in a plane that is oblique to the side and top surfaces thereof, 20 with the end and upper edge surfaces of said blade projecting respectively outward of the side and top surfaces of said raised portion.
- 25 3. A scraper blade sharpening tool comprising a body having a raised rectangular portion with a groove at one side thereof and with a guide surface outward of said groove slightly above the bottom thereof,

but below the top of said rectangular raised portion, and a hard sharpening blade set 30 into the said raised portion of said body in a plane that is oblique to the upper and side surfaces thereof, and with the edges of said blade projecting outward of said surfaces.

4. A scraper blade sharpening tool comprising a body having a raised rectangular portion with a groove at one side thereof, 35 and with a guide surface outward of said groove slightly above the bottom thereof, but below the top of said rectangular raised 40 portion, and a hard sharpening blade set into the said raised portion of said body in a plane that is oblique to the upper and side surfaces thereof, and with the edges of said blade projecting outward of said surfaces, 45 the said body, at one projecting edge, having a groove adapted to receive a portion of a file.

In testimony whereof we affix our signatures in presence of two witnesses.

CHARLES J. BRUNSELL.
JOHN JOHNSON.
